United States Patent Office.

S. J. PEET, OF NEW YORK, N. Y.

Letters Patent No. 100,318, dated March 1, 1870; antedated February 16, 1870.

IMPROVEMENT IN APPARATUS FOR MAKING SOLID CORES.

The Schedule referred to in these Letters Patent and making part of the same.

To all whom it may concern:

Be it known that I, S. J. PEET, of the city, county, and State of New York, have invented a new and improved Machine for Making Solid Cores; and I do hereby declare the following to be a full, clear, and exact description thereof, which will enable those skilled in the art to make and use the same, reference being had to the accompanying drawing forming part of this specification, in which—

Figure 1 represents a longitudinal vertical section of this invention.

Figure 2 is a transverse vertical section of the same. Similar letters indicate corresponding parts.

This invention relates to a machine for making solid cores, which is composed of a stationary table, forming the support for the core-plate, and the guide for a rising and falling gate, which supports the templet-plate.

On this templet-plate is laid the hopper-plate, through the funnel-shaped apertures of which the sand is introduced into the holes in the templet-plate, and the sand is rammed down with the required uniform degree of force by a series of rams or stamps secured to a common head or follower, which is depressed by a hand-lever or otherwise.

After the sand has been rammed down sufficiently tight, the hopper-plate is shoved off from the templet-plate horizontally, thereby carrying off the surplus sand, and smoothing down the surface of the cores, and by rapping the templet-plate the cores contained therein are loosened, so that when the templet-plate is raised said cores are deposited upon the core-plate, which, together with the cores, can be easily removed.

In the drawing, the letter A designates a frame made of wood or any other suitable material.

This frame supports a platform or table, B, which is provided with a recess to receive the core-plate C, which is cast of type-metal, or made of any other suitable material, and as thin as may be compatible with the required strength.

Through the table B extend two standards D D, the bottom ends of which are connected by a strong inverted roof-shaped bar, E, while their top ends form the supports for the templet-plate F, which is firmly secured to the same, and which is provided with a series of apertures or holes to correspond to the cores to be formed.

The inverted roof-shaped bar E is acted on by a cam, G, which is mounted on a shaft, H, extending transversely across the frame A, and being so arranged that it can be revolved either by hand, foot, or other power. By turning said shaft, the cam G bears

against the bar E, and the templet-plate F is raised from the table B.

On the templet-plate F is placed the hopper-plate I, which is cast of metal in a similar mold to the templet-plate, and perforated by the same number of holes, being of the same shape as those in the templet-plate, except that they are made a little bell-mouthed to receive the sand or other substance for the cores.

When each core-box and its hopper shall have received its proper amount of sand, they are all stamped or rammed by a ganged force by means of a series of rams or stamps, J, which are attached to a common head, K, that slides up and down on guide-bars L, and is exposed to the action of springs a, which have a tendency to raise the same up to the position shown in the drawing.

From said head extend rods b to levers c, which extend from a rock-shaft, d, so that by imparting to this rock-shaft an oscillating motion, the head is raised or lowered, and by depressing the head the several rams are brought into action, and the sand in the core-boxes is compressed with the required force.

After the sand has been compressed, the rams are raised and the hopper-plate I is shoved off from the templet-plate in a horizontal direction, so that the surplus sand is carried off, and the upper surface of the cores is smoothed down.

The cores in the templet-plate are then liberated by a few raps, and by a gentle motion of the cam G the templet-plate is raised, while the cores are deposited on the core-plate C, which being loose can be easily removed, and together with the cores introduced into a drying-kiln or oven, while another core-plate is put in its place, and the same process is repeated.

By these means the operation of making cores is simplified, so that it can be readily performed by children, and by changing the templet-plate, the hopper-plate and the rams of my machine can be used for molding solid cores of any desired description.

Having thus described my invention,

What I claim as new, and desire to secure by Letters Patent, is—

The rising and falling standard D D, in combination with the templet-plate F, table B, core-plate C, hopper-plate I, and stamps J, all constructed substantially in the manner herein shown and described.

This specification signed by me this 17th day of June, 1869.

S. J. PEET.
